[57] **CLAIM**

The ornamental configuration of a carrying case for spools of thread, as shown in the drawing figures and described herein.

DESCRIPTION

FIG. 1 is a top, right, front perspective view of my design for a carrying case for spools of thread with the carrying case shown in the closed position with the left side being the mirror image of the right side;

FIG. 2 is a rear elevational view of the carrying case shown in the closed position;

FIG. 3 is a bottom plan view of the carrying case shown in the closed position;

FIG. 4 is a top front right perspective view of the carrying case shown in the open position with the left side being the mirror image of the right side and illustrating spools of thread in phantom lines; and,

FIG. 5 is a bottom plan view of the carrying case shown in the open position.
